SOFFIT REENFORCEMENT

Alan Price Wilson, Falls Church, Va.

Application September 20, 1932
Serial No. 634,036

9 Claims. (Cl. 72—109)

The invention relates to improvements in flange caging which result in a continuous caging having transverse or cross members (for anchoring the fireproofing material to the flange of the structural steel) spaced on any predetermined centers, but with the longitudinal (connecting and spacing) member located outside of the line of flow of the plastic material around the edge and past the face of the flange, where it cannot induce voids or imperfections in the thin fireproofing of the flange face, hereinafter called the "soffit area," and as appears in Figure 1 this longitudinal member is itself outside the soffit area with self-contained means of keeping the cross members, which anchor the soffit area fireproofing to the steel flange, in the approximate center of the soffit fireproofing and with self-contained means of adjusting a standard length cross member to a plurality of flange widths.

The transverse or cross member, *a*, is provided with a hook at one end to engage one edge of the flange, and a plurality of projections, which may be humps, *b*, serving to keep it away from the face of the flange regardless of the point at which the cross member is bent around the other edge of the flange, this bend being a field operation. Close contact with this last mentioned edge of the flange is avoided by making the cross member of a material so stiff that when the field bend is made it will spring free from the edge of the structural steel and thus reenforce the concrete in the region outward from the flange edge. The factory-formed hook, *c*, is held the desired distance from the flange edge by stops or interferences, *d*, on the longitudinal spacing member, *e*, which butt against or engage the edge of the flange.

The location of the longitudinal members outside the soffit area also facilitates shipping of large quantities of the caging nested within small compass because the caging elements can be crated or uncrated without the tangling of parts, the longitudinal element not interfering with the humps on the transverse members during crating and uncrating.

In its broader aspects this invention is not limited to humps or projections on the transverse member, but for transverse members intended to be adapted to different width flanges it is advantageous to have three or more humps.

The term "soffit area" as used in this specification means that portion of the concrete or other fireproofing which, in a beam or girder, lies below the plane of the outer face of the bottom flange of the structural-metal member, and, in a column, lies outside of the plane of the outer face of either flange of the structural-metal member.

I claim:

1. Flange caging for structural metal members having longitudinal and transverse members, the

longitudinal member having means thereon to engage the edge of the flange, thereby providing a stop, and the transverse member having projections thereon to hold it away from the flange.

2. Flange caging for structural metal members having longitudinal and transverse members, the longitudinal member having means thereon to engage the edge of the flange and to cause the transverse member to project outward from the flange edge, thus providing a gap or space between the caging and the edge of the flange and reenforcing the concrete in this region.

3. Flange caging for structural metal members having a longitudinal member, a transverse member, and means on the longitudinal member to cause a portion of the caging to project outward beyond the flange edge, thus providing a gap or space between the caging and the edge of the flange and reenforcing the concrete in this region.

4. Flange caging for structural metal members having longitudinal and transverse members, a longitudinal member being located outside and at the side of the soffit area.

5. Flange caging for structural metal members having longitudinal and transverse members, the transverse members being spaced away from the flange edge to reinforce the concrete in this region, and provided with a plurality of projections to hold them away from the surface of the flange and to adapt them to fit different width flanges, the spaced away portion encompassing the flange of the structural member.

6. Flange caging as defined in claim 5 especially adapted to nesting within small compass and to crating and uncrating without tangling of parts, the projections consisting of humps and the longitudinal members being located at the side of the humps so as to avoid interference with the humps during crating and uncrating.

7. A transverse member for flange caging, in part at least of stiff wire material, characterized by the fact that a projection which engages the flange surface, cooperates with the stiffness of the material to cause the flange engaging ends of the member to spring free of the edge of the flange.

8. Flange caging for structural metal members having transverse members, means to hold them away from the flange, and a longitudinal for spacing apart the transverse members, the longitudinal being located at the side of the soffit area so that the soffit area is wholly unobstructed by it.

9. In a flange caging for structural metal members, the combination of spacing and connecting members placed outside the soffit area with cross members spaced away from the face of the flange by mechanical elements thereon and from the edge of the flange by the stiffness of the material thereof.

ALAN PRICE WILSON.
